Attorney

UNITED STATES PATENT OFFICE.

MARK EUGENE MOORE, OF MINNEAPOLIS, MINNESOTA, ASSIGNOR TO MOORE TOOL COMPANY, OF FAIRMONT, MINNESOTA, A CORPORATION OF MINNESOTA.

EXPANDING MANDREL.

1,343,273.

Specification of Letters Patent. Patented June 15, 1920.

Application filed November 12, 1919. Serial No. 337,416.

To all whom it may concern:

Be it known that I, MARK EUGENE MOORE, citizen of the United States, residing at Minneapolis, in the county of Hennepin and

5 State of Minnesota, have invented certain new and useful Improvements in Expanding Mandrels, of which the following is a specification, reference being had to the accompanying drawings.

10 This invention relates to an improved expanding mandrel or sleeve particularly adapted for use in connection with the arbor of a lathe, and an object of the invention is to provide an expanding mandrel or

15 sleeve which is capable of expansion and contraction, in such wise that its diameter will remain uniform throughout its length.

Another object of the invention is to provide a mandrel or sleeve of this kind, which 20 insures against distortion of the work carried by the mandrel or sleeve at all points of the expansion, regardless as to how fragile the work might be.

A further object of the invention is to 25 provide a mandrel or sleeve, capable of carrying work of all sizes, and furthermore to insure considerable friction between the work and the sleeve or mandrel at all points, thereby acting to securely hold the work on the mandrel.

A still further object of the invention is to provide a mandrel or sleeve for use on a lathe arbor having contracting ends adjacent the circular openings of the slots, so as 35 to take care of the buckling at the end of the mandrel when the sleeve or mandrel expands, thereby preventing distorting the work.

While the design and construction at present illustrated and set forth is deemed preferable, it is obvious that as a result of a reduction of the invention to a more practical form for commercial purposes, the invention may be susceptible to changes, and 40 the right to these changes is claimed, provided they are comprehended within the scope of what is claimed.

The invention comprises further features and combination of parts, as will be herein- 50 after set forth, shown in the drawings and claimed.

In the drawings:

Figure 1 is a view in elevation of a lathe arbor, showing the improved expanding 55 mandrel or sleeve applied thereto.

Fig. 2 is an enlarged detail view of the sleeve or mandrel showing the same expanded, and also showing a part of the mandrel or sleeve in section.

Fig. 3 is a cross sectional view on the 60 line 3—3 of Fig. 2.

Referring more especially to the drawings 1 designates a lathe arbor which may be of any suitable construction, preferably gradually tapered as shown and 2 denotes an ex- 65 panding mandrel or sleeve.

This sleeve or mandrel may be constructed of any suitable metal, preferably steel and which is designed to fit the arbor. The sleeve or mandrel is provided with a 70 plurality of slots or slits 3 which extend longitudinally thereof and are staggered. In other words, certain of the slits or slots are formed from one end of the sleeve or mandrel and terminate in very close positions adjacent the opposite ends, while the remaining slots or slits are reversely constructed. Where the slits terminate short of the ends of the sleeve or mandrel circular openings 4 and 5 are formed. Where 75 these openings 4 and 5 occur, the end portions of the mandrel or sleeve are provided with shoulders 6, and from the shoulders the end portions of the sleeve are reduced, as shown at 7. It will be noted that when the 80 sleeve or mandrel is slipped telescopedically on the arbor, it will readily expand, and it is to be understood that as the sleeve or mandrel passes over the arbor, and is finally arranged in position, its cylindrical contour 85 remains uniform throughout its length, so as to properly hold the work, which is designed to be carried by the mandrel or sleeve. Furthermore, owing to the expansion of the sleeve or mandrel at all points, 90 the work, regardless of how fragile it might be, is prevented from distorting. Also the work to be turned will fit frictionally on the sleeve, and will contact therewith at all points, and furthermore the work when fin- 95

ished may be easily and very quickly released. Owing to the opposite ends of the sleeve or mandrel being reduced as indicated at 7, the buckling which usually occurs at the ends of the sleeve or mandrel is read- 100 ily taken care of.

The sleeve or mandrel is so constructed as to remain substantially perfectly cylindrical at all points, thereby preventing distorting the work, or in other words pre- 110

venting pulling out of the cylindrical contour of the work. In devices heretofore used, the sleeve or mandrel eventually becomes distorted, which will distort the fragile pieces of work which are constructed on the arbor.

The sleeve or mandrel is finished so that the portions between the slots or slits have their bearing surfaces formed on the arch 10 of a circle, whose diameter is exactly the maximum diameter to which the sleeve expands. In other words, when the sleeve or mandrel is contracted, the outer bearing surfaces as well as the inner bearing surfaces 15 of the parts between the slots are curved so that each of their radii will constitute a radius of a circle whose diameter corresponds to the diameter of the circle to which the parts between the slots are adapted to expand, namely the maximum 20 diameter. The sleeve or mandrel is constructed in this manner so that when the sleeve is expanded, it will not only truly fit the arbor but will also fit the work, 25 which is adapted to be mounted upon the sleeve or mandrel in order to prevent distorting or breaking of fragile work, which may be carried by the sleeve or mandrel.

The inside surface of the sleeve is tapered 30 so as to fit the tapered arbor. It has been found that by reducing the ends of the sleeve or mandrel, as shown, the ends of the sleeve where the buckling usually occurs, the work when applied to the sleeve or mandrel will be offset. Owing to the reduction 35

of the ends of the sleeve or mandrel, the parts between the slots are allowed to expand, and the extremities of these parts are not permitted to come in contact with the work, which has been found very important in the construction of expandable mandrels or sleeves. 40

The invention having been set forth, what is claimed as new is:—

The combination with a lathe arbor, of 45 a sleeve or mandrel adapted to telescopically fit the arbor, said sleeve or mandrel having longitudinal slits constructed in the wall thereof and being formed from opposite ends of the mandrel, whereby the mandrel 50 or sleeve is capable of expanding when fitted upon the arbor, said slits having their closed ends terminating short of the opposite ends of the sleeve or mandrel and staggered with relation to the open ends of the 55 slits, whereby the opposite ends of the mandrel or sleeve can uniformly expand, the closed ends of the slits terminating in circular openings, thereby permitting the sleeve or mandrel to readily expand, the opposite ends of the mandrel or sleeve being reduced and having shoulders immediately adjacent the circular openings at 60 the closed ends of the slits, thereby taking care of the buckling, which usually occurs 65 when the sleeve expands.

In testimony whereof I hereunto affix my signature.

MARK EUGENE MOORE.
